UNITED STATES PATENT OFFICE

MARTIN LOWITZ, OF NEW YORK, N. Y.

DESIGN FOR A VEGETABLE OR FRUIT SLICER OR THE LIKE ARTICLE

Application filed July 29, 1931. Serial No. 40,710. Term of patent 7 years.

To all whom it may concern:

Be it known that MARTIN LOWITZ, a citizen of Germany and resident of New York city, in the county of New York and State of New York, has invented a new, original, and ornamental Design for a Vegetable or Fruit Slicer or the Like Article, of which the following is a specification, reference being had to the accompanying drawing, forming part thereof, in which,

The figure is a perspective view of a vegetable or fruit slicer embodying my new design.

I claim:

The ornamental design for a vegetable or fruit slicer or the like article, substantially as shown.

Dated New York city, June 29th, 1931.

MARTIN LOWITZ.
